United States Patent Office

Des. 222,282
Patented Oct. 12, 1971

222,282

SNOW BOARD

Loran R. Hill, Olney, Ill., assignor to
AMF Incorporated

Filed May 7, 1970, Ser. No. 22,870

Term of patent 14 years

Int. Cl. D21—03

U.S. Cl. D34—15

FIG. 1

FIG. 2

FIG. 3

FIG. 4

FIG. 1 is a top perspective view of a snow board showing my new design; and

FIG. 2 is a bottom perspective view of the snow board; FIG. 3 is a bottom plan view thereof; and

FIG. 4 is a side elevation view thereof.

I claim:

The ornamental design for a snow board, substantially as shown.
